D. H. LADD

IGNITION WIRING AND CONDUCTOR FOR INTERNAL COMBUSTION ENGINES

Filed April 21, 1921

Inventor

DONALD H. LADD;

By

R. S. Morris

Attorney

UNITED STATES PATENT OFFICE.

DONALD H. LADD, OF TORRANCE, CALIFORNIA.

IGNITION WIRING AND CONDUCTOR FOR INTERNAL-COMBUSTION ENGINES.

Application filed April 21, 1921. Serial No. 463,235.

To all whom it may concern:

Be it known that I, DONALD H. LADD, a citizen of the United States, and resident of Torrance, in the county of Los Angeles and 5 State of California, have invented certain new and useful Improvements in Ignition Wiring and Conductors for Internal-Combustion Engines, of which the following is a specification.

10 My present invention particularly pertains to electrical conductors and their connections for timers or commutators, and especially relates to an attachment for timers of the Ford type such as are used 15 with the internal combustion engines on Ford automobiles and tractors.

Timers of the Ford type embody an oscillatory cylindrical shell having a series of 20 radially extending binding posts on its outer periphery to which the terminals of electrical conductors are fastened and which conductors have a flexible length leading from the shell to permit turning of the latter, and with the flexible conductors extending 25 from the shell in such fashion as to bend when the shell is turned. This bending of the conductors may cause them to break and thereby result in shorting or interruption of the electrical circuit so as to interfere with 30 the ignition circuit controlled by the timer.

An object of my invention is to provide a device whereby a twisting movement will be imparted to the flexible lengths of conductor leading to the timer shell or turning the shell without effecting a bending action thereon, so as to obviate breaking the conductor, it being found that a wire is less apt 35 to break when a length is twisted than when abruptly bent as the molecular movement in 40 the wire is distributed over a greater portion of the wire.

Another object is to provide a conductor mounting adapted to be readily attached to a commutator shell and by which a series of 45 flexible conductors may be fastened at and extend from a point in alignment with the axis of the turnable commutator shell.

In carrying out the foregoing objects I employ the parts, and the combination and 50 arrangement of parts hereinafter described and claimed and illustrated in the accompanying drawing, in which:—

Figure 1 is a view in side elevation of a timer showing the invention applied.

55 Fig. 2 is a view in front elevation.

Fig. 3 is a view in elevation of an insulating block employing in the device.

Fig. 4 is a view in elevation of a bracket for carrying the insulating block shown in 60 Fig. 3.

Fig. 5 is a view in perspective showing the conductor bracket and terminal block to be carried by the timer shell.

In the drawings 6 indicates a cylindrical timer or commutator shell mounted to oscillate on a wall 7 and adapted to be turned on an axis by a rod 8 and which shell is provided with a series of radially extending binding posts 9, 10, 11 and 12 on its outer periphery, as is common in timers of the 70 Ford type.

In carrying out my invention I provide a bracket 13 to be mounted on the shell which bracket is formed of four stiff insulated wires, 14, 15, 16 and 17, which are bound together intermediate their ends by a tape winding 18 whereby the bracket is formed with a rigid shank portion 19.

The inner ends of the wires 14, 15, 16, and 80 17 are designed to be connected to the binding posts 9, 10, 11 and 12, and the wires are arranged so that the shank will extend outwardly from the end of the shell. The outer ends of the wires are connected to binding posts 20, 21, 22 and 23, carried on an insulating block 24, whereby the block is supported on a bracket in spaced relation to the shell with the center of the block located in alignment with the axis of rotation of the shell. The bracket 19 being rigid, the insulated block 24 will be held in rigid relation 90 to the shell and will move in unison therewith on a corresponding axis of rotation.

A bracket 25 mounted on the wall 7 carries an insulated block 26 provided with binding posts 27, 28, 29 and 30 to which are connected conductors 31, 32, 33 and 34 leading to the points of distribution. Connecting with the binding posts on the block 26 are two pairs of twisted junction conductors 35 and 36 which are bowed outwardly and downwardly from the block 26, and are passed through an opening 37 formed in the center of the block 24; the conductors in the pairs 35 and 36 being connected to the binding posts on the block 24 to effect electrical connection with the several conductors forming the bracket 19.

In the operation of the invention turning movement of the timer shell will effect a 110

corresponding movement of the insulator block 24, which, because of the twisted conductors connecting with the center of said block in alignment with the axis of rotation 5 of the block and shell will cause a twisting movement to be imparted to these conductors, which, being flexible, the twisting action thereon will be distributed throughout a substantial length thereof, thus rendering 10 the possibility of breaking the conductor by such twisting movement very remote.

I claim:

1. An ignition wiring and conductor attachment for timers embodying an oscillatory shell, and a series of binding posts on said shell, and a series of conductors attached to said binding posts and formed to provide a stiff bracket projecting from the end of the shell, and flexible conductors connecting with said bracket conductors substantially in alignment with the axis of rotation of said shell.
2. An ignition wiring attachment for timers embodying an oscillatory shell and 25 a series of binding posts on said shell; a series of stiff wire conductors connecting with the binding posts on said shell and formed to provide a stiff bracket projecting from the end of the shell, an insulating block carried 30 by said conductors and arranged in front of and in spaced relation to the end of the shell,

and a series of flexible conductors connecting with said block and extending therefrom in alignment with the axis of rotation of said shell, said flexible conductors being electrically connected to the stiff conductors. 35

3. In an ignition wiring attachment for timers, the combination of an oscillatory shell, a series of binding posts on said shell, a series of flexible conductors, and 40 means for electrically connecting said conductors to the binding posts on said shell whereby said conductors will approach said shell axially thereof and adjacent the center of oscillation thereof. 45

4. In a wiring system for internal combustion engines, the combination of a turnable timer shell, and conductor wires electrically connected to said timer shell, said conductor wires approaching said timer shell 50 in a line which is close to and parallel with a line in alignment with the axis of rotation of said timer shell whereby said conductor wires receive only a slight movement when the timer is oscillated on its axis. 55

In testimony whereof I have signed my name to this specification in the presence of two subscribing witnesses.

D. H. LADD.
